UNITED STATES PATENT OFFICE.

ALFRED SMALLWOOD, OF LONDON, ENGLAND.

FURNACE.

1,351,801.

Specification of Letters Patent. Patented Sept. 7, 1920.

Application filed July 31, 1918. Serial No. 247,645.

To all whom it may concern:

Be it known that I, ALFRED SMALLWOOD, a subject of the King of Great Britain, residing at 42 Hargrave Park, Highgate, London, N., in the county of Middlesex, England, metallurgist, have invented Improvements in or Relating to Furnaces, of which the following is a specification.

This invention comprises certain improvements in or relating to furnaces, and refers particularly to furnaces adapted to be heated by gaseous, vaporous, or liquid fuel.

According to the present invention, air for combustion is adapted to be admitted to the fuel at a point removed from the point of primary ignition. Air for the primary ignition may be admitted to a Bunsen burner, and the mixture may be fired at the mouth of the burner in a chamber. The secondary air may be admitted to the mixture after it has substantially traversed this chamber.

A feature of the present invention resides in the fact that a secondary air system such as this is pluralized in conjunction with a single furnace or heating chamber. Advantageously such a secondary air system is employed in conjunction with each Bunsen burner, although two or more burners may if desired be combined with each secondary air system. By the employment, however, of a series of substantially separate systems, each having its burner or burners and secondary air supply, a particularly effective grading and distribution of the heat may be obtained.

The systems may be arranged in pairs located in opposed formation so that one of each pair is adapted to supply heat to each side or end of the same goods chamber.

In order that this invention may be clearly understood and readily carried into practice, reference may be had to the appended explanatory sheets of drawings, upon which:—

Figure 1 is a sectional end elevation of a furnace according to the present invention, the plane of section being on line 1—2 of Fig. 2.

Fig. 2 is a sectional plan of the furnace shown in Fig. 1, the plane of section being on line 3—4 of Fig. 1 and line 5—6 of Fig. 3.

Fig. 3 is a sectional end elevation of the furnace shown in Figs. 1 and 2, the plane of section being on line 7—8 of the figure last mentioned.

Fig. 4 is a sectional plan on line 9—10 of Fig. 1.

Fig. 5 is a sectional elevation on line 11—12 of Figs. 1 and 4, and 60

Fig. 6 is a sectional elevation on line 13—14 of Fig. 1.

In a convenient embodiment of the present invention, there are provided below the floor of a heating chamber *a*, a series of, 65 say, six or eight isolated or substantially isolated chambers *b*. These may be in aligned pairs located transversely at intervals along the furnace. Two vertical partitions *c* are located longitudinally in each chamber. 70 These partitions are adapted to form a central chamber or flue and two flues *d* one on each side of said central chamber or flue, these side flues being in communication with the central chamber or flue at the extremity 75 thereof remote from the side of the furnace. With the extremity of the central chamber adjacent to the side of the furnace a Bunsen burner is placed in communication by way of a port *e* with which a primary air 80 inlet *e*¹ may communicate. At their extremities near to the side of the furnace the side flues *d* communicate with the heating chamber *a* or jacket space or the like for heating the same, for which purpose said 85 flues *d* adjoin each other at *f* to enter spaces *s* and communicate by a common port *g* with the goods chamber *a*. To permit of this the port *e* may communicate with the lower part of the central chamber *b* and the 90 side flues *d* may extend to positions one on each side of the port *e*; the connecting passage *f* between the side flues *d* may be located above the port *e*.

If desired, connecting flues may be provided 95 between the inner extremities of chambers occurring on opposite sides of the furnace, which chambers may appertain to different pairs.

Below each chamber a horizontal air flue 100 *h* is provided. This air flue *h* extends inwardly of the furnace substantially the length of the chamber *b* and communicates by upward ports *i* with the central chamber *b* and with the two side flues *d* at the ends 105 of said chamber and side flues remote from the outer wall of the furnace. The fuel is thus enabled to be partially fired in the central chamber *b*, after which the air admitted thereto enables the secondary and complete 110 firing to take place in the flues *d*.

By virtue of the disposition of the air

flues below the chambers the air is heated in said flues by heat radiated downwardly. Alternatively or additionally, however, the air in the secondary air supply flues may be 5 heated by the waste furnace gases, for which purpose the latter may be passed through flues arranged in the vicinity of said air flues. To permit of this, flues for the waste gases are carried downwardly to the vicinity 10 of the air flues so that the air flues may be located in such a position that it is unnecessary to draw the air downwardly into the goods chamber in a manner necessitating the latter being under closed conditions.

15 One embodiment of the former of the two alternatives last mentioned is illustrated in the drawings, in which the heating gases are adapted to egress from the goods chamber *a* by two ports *j* located one on each side 20 of the goods chamber *a* at one extremity thereof. These ports *j* extend inwardly and communicate at *k* with two longitudinal flues *l* located between the systems *b*, *d* and the air flues *h*. After having traversed the 25 length of the furnace in the flues *l*, the gases are adapted to pass by way of connecting ports *m* into flues *n*, in which latter the gases again traverse the length of the furnace. The gases then pass by way of connecting 30 ports *o* into two longitudinal flues *p* which extend the length of the furnace and adjoin a vertical flue *q* by which they are conveyed to the stack.

r represents a small heating gas outlet located at the end of the goods chamber remote from that at which the outlets *j* are provided. This outlet *r* communicates with the flue *q*, and enables the heat to be more satisfactorily distributed within the goods 40 chamber. In the case of long furnaces, or in any case where desired, additional outlet ports may be provided at the side or sides of the goods chamber or in the roof thereof, these outlets being in communication with the stack, as for instance by way of a longitudinal jacket flue in the crown through which the gases from the flue *q* may pass before passing to the stack.

What I claim as my invention and desire 50 to secure by Letters Patent is:—

1. A furnace adapted to be heated by gaseous or liquid fuel, including in combination with a goods chamber, means for introducing air for primary combustion, and 55 means independent of said first named means for introducing air for secondary combustion at a point removed from the point of primary combustion.

2. In a furnace adapted to be heated by 60 gaseous or liquid fuel, in combination a goods chamber, a plurality of isolated chambers beneath said goods chamber, each of

said isolated chambers provided with two vertical partitions adapted to form a central passage and two flues, said flues being in 65 communication with the central passage at one extremity and with the goods chamber at the other extremity.

3. In a furnace adapted to be heated by gaseous or liquid fuel, in combination a 70 goods chamber, a plurality of isolated chambers beneath said goods chamber, each of said isolated chambers provided with two vertical partitions adapted to form a central 75 passages and two flues, said flues being in communication with the central passage at one extremity and with the goods chamber at the other extremity, and horizontal air flues adapted to permit ingress of air to the flues at the extremity at which they communicate with the central passage.

4. In a furnace, in combination with a goods chamber, a plurality of isolated chambers beneath said goods chamber, each of said isolated chambers provided with two 85 vertical partitions adapted to form a central passage and two flues, said flues being in communication with the central passage at one extremity and with the goods chamber at the other extremity, horizontal air flues 90 adapted to permit ingress of air to the flues at the extremity at which they communicate with the central passage, longitudinal flues located between the air admission flues and the isolated chambers, and communicating 95 with one end of said goods chamber to provide a path for the waste furnace gases.

5. In a furnace, in combination with a goods chamber, a plurality of isolated chambers beneath said goods chamber, each of 100 said isolated chambers provided with two vertical partitions adapted to form a central passage and two flues, said flues being in communication with the central passage at one extremity and with the goods chamber 105 at the other extremity, horizontal air flues adapted to permit ingress of air to the flues at the extremity at which they communicate to the central passage, longitudinal flues arranged between the air admission 110 flues and the isolated chambers communicating with one end of said goods chamber to provide a path for the waste furnace gases, and additional longitudinal flues arranged below the air admission flues and 115 communicating with said first named longitudinal flues at the end opposite to the one communicating with the goods chamber.

In witness whereof I have hereunto set my hand in the presence of two witnesses. 120

ALFRED SMALLWOOD.
